UNITED STATES PATENT OFFICE.

CHARLES TRIBBY, OF WASHINGTON, DISTRICT OF COLUMBIA.

IMPROVEMENT IN LAMPS.

Specification forming part of Letters Patent No. 123,749, dated February 13, 1872.

To all whom it may concern:

Be it known that I, CHARLES TRIBBY, of Washington city, in the county of Washington and District of Columbia, have invented a new and useful Improvement in Lamps for Burning Coal-Oils of different kinds, of which the following is a full, clear, and exact description, reference being had to the accompanying drawing and the letters of reference marked thereon making part of this specification, in which is represented a vertical sectional view of the lamp.

The nature of my invention consists in securing in the reservoir of the lamp a tube, so arranged that all the inflammable and explosive gases generated shall be discharged at the base of the lamp, in combination with a perforated flange and drip-cup.

The great advantage of this arrangement is, that any of the oils now in general use, such as naphtha, &c., can be burned with perfect safety.

The great danger with oils of the class referred to arises from the fact that the intense heat of the burner generates from the oil in the reservoir a gas of a most inflammable nature, and which explodes the moment the flame or other blaze is brought in contact therewith; all danger of which with my improvement is securely guarded against, as the gas escapes at the base of the reservoir, and passes off through the perforated flange; and which, in addition to the drip-cup which receives and retains all the oil which, in filling or moving the lamp, may escape by the gas-tube, furnishes a neat and effective device for rendering the lamp perfectly safe, no matter what the character of the oil or fluid burned in the same may be.

The construction and operation of my invention is as follows: A is the reservoir of the lamp, which is constructed of any desired form and of any suitable material. B is the burner, and may be of any of the numerous approved patterns. This burner is screwed into the neck of the reservoir in the usual manner, and is in no particular new, excepting that its joints are all air-tight. C is the wick-winder, and, instead of working in open orifices cut through the wall of the burner, it is secured in a close socket-bearing, c, and an open sleeve, c'. On the shank of the wick-winder is a coil-spring, D, which so presses on a rubber washer, d, that encircles the wick-winder as to form an air-tight connection or joint at the mouth of the sleeve. E is a tube, secured in the lower wall of the reservoir, and running vertically up through the same to near its dome, as clearly shown in the drawing. Around the lower section of the base of the lamp is an annular flange, a, over which fits a drip-cup, A'. This flange is so perforated at a' as to permit the escape of the gas as it descends from the tube E, which both discharges the gas and supplies air to fill the reservoir as the oil is consumed.

What I claim as new, and desire to secure by Letters Patent of the United States, is—

The lamp-reservoir A, tube E, perforated flange a, and drip-cup A', when the same are combined and arranged as described.

In testimony whereof I have signed my name to this specification in the presence of two subscribing witnesses.

CHARLES TRIBBY.
